United States Patent Office

Des. 220,422
Patented Apr. 13, 1971

220,422

CAN OPENER OR THE LIKE

Thomas E. Hanson and William L. Wolfe, Syracuse, N.Y.,
assignors to Proctor-Silex Incorporated, Philadelphia, Pa.

Filed Apr. 9, 1970, Ser. No. 22,358

Term of patent 14 years

Int. Cl. D8—02

U.S. Cl. D8—36

FIG. 1 is an isometric view of a can opener embodying our new design;

FIG. 2 is a right side elevational view;

FIG. 3 is a rear elevational view;

FIG. 4 is a left side elevational view; and

FIG. 5 is a top plan view.

We claim:

The ornamental design for a can opener or the like, as shown.
